UNITED STATES PATENT OFFICE.

HANS TECHEL, OF KIEL, GERMANY, ASSIGNOR TO FRIED. KRUPP AKTIENGESELLSCHAFT GERMANIAWERFT, OF KIEL, GERMANY.

AMMUNITION HOIST.

1,425,916.

Specification of Letters Patent. Patented Aug. 15, 1922.

Application filed January 3, 1921. Serial No. 434,635.

To all whom it may concern:

Be it known that I, HANS TECHEL, residing at Kiel, Germany, a citizen of the German Republic, have invented a certain new and useful Improvement in Ammunition Hoists, (for which I have filed application in Germany, filed July 15, 1918), of which the following is a specification.

This invention relates to ammunition hoists, in particular those which are operated by means of compressed air, and which are provided with a charging tube adapted to be swung underneath the hoisting tube. The object of the invention is to provide a construction, both simple and yet working with perfect reliability, by means of which the close connection required for a perfect hoisting will be established between the charging and the hoisting tube.

20 The invention will be further described with reference to the accompanying drawing which shows, by way of example, two embodiments of the subject matter of the invention and in which—

25 Fig. 1 is a side view, partly in section, of the first form of execution of the improved ammunition hoist,

Fig. 2 is a pertinent section on line 2—2 in Fig. 1, seen from the top, and

30 Fig. 3 is a similar view as shown in Fig. 1, of the second form of execution.

The form of execution illustrated in Figs. 1 and 2 will be described first.

The hoist has a hoisting tube A, underneath which an S-shaped body D (see Fig. 2) serving to receive two charging tubes F, is adapted to swing about a vertical axis E. Said charging tubes can be tilted about the axes of horizontal pivots f^1 engaging 35 supports d^1 arranged on the body D, a certain amount of play in the perpendicular sense being allowed to the pivots f^1 within the support d^1 . Each charging tube F is provided with a hoisting piston G on which 40 the ammunition to be hoisted, a shell B for example, is placed. On their upper ends the charging tubes have a flange f^2 adapted to bear up against a flange a^2 of the hoisting tube A.

50 Each of the two charging tubes which happens to contain ammunition to be hoisted, forms, when swung into its operative position, a continuation of the hoisting tube A; in this contingency it is located above 55 a ram H displaceable within a cylinder J and serving to force the flange f^2 of the

charging tube against the flange a^2 of the hoisting tube. Air pipes 1, 2, connected to the cylinder J communicate with the casing K of a piston-shaped distributing valve L. 60 From the casing K two pipes, 6 and 7, run to a compressed air receiver P, while another pipe 8 leads to the outside. A spring T tends to maintain the distributing valve L, which is adapted to be displaced counter 65 to the spring action by means of a hand lever W, in its lowermost position in which the pipes 1 and 7 are cut off.

At the upper end of the hoisting tube A is located a bell crank lever M, one arm of 70 which is connected to the body of a valve N, whereas its other arm supports a roller m^1 which, when the valve is closed, projects through a narrow slot a^3 into the tube A. A pipe 3 connected to the compressed air receiver P, terminates in the valve box below the valve seat while thereabove is arranged a pipe 4 which for its part terminates above the distributing valve L in the casing K. Besides, there are arranged in the upper 75 section of the tube A a slot a^1 and a pawl O provided with a handle o^1 ; said pawl being adapted to project through a slot a^3 into the tube A under the action of a spring o^2 .

80 A pipe 5 runs from the casing K of the distributing valve to the flange a^2 of the hoisting tube A. To the flange f^2 of each of the charging tubes F there is connected a pipe 5^1 . This arrangement is such that the compressed air is enabled to flow from pipe 85 5 into one of the pipes 5^1 and consequently below the hoisting piston G, provided the flanges a^2 , f^2 are pressed against each other.

The manner of operation of the device is 90 as follows:

95 One of the charging tubes F having been charged and tilted into the perpendicular position, it is shifted, by swinging the body D around the axis E, underneath the hoisting tube A and therewith, at the same time, 100 above the ram H. Upon this, the distributing valve L is lifted by means of the hand lever W out of the position, in which it cuts off the pipes 1 and 7, into the position shown in the drawing in which it permits the compressed air flowing from the receiver P through pipe 7 into the valve casing K, to freely pass through the pipe 1 into the cylinder J. The ram H, forced upward by the compressed air, bears up against the bottom 110 of the charging tube F and presses the flange f^2 tight against the flange a^2 of the

hoisting tube A. By these means a mutual connection is established between the pipes 5 and 5¹ so that as the distributing valve L continues to be lifted from its seat, the compressed air will now be enabled to flow from the receiver P through pipe 6, through a grooved portion 7¹ of the valve L and pipes 5, 5¹ underneath the hoisting piston G. Owing to the pressure exerted by the hoisting medium, the charged hoisting piston is driven upward to the place where the ammunition is taken off. In passing the roller m¹, the hoisting piston G forces this latter outward and thus causes the valve N to be opened, so that the compressed air is now enabled to travel from the receiver P through pipes 3 and 4 to the casing K of the distributing valve. Almost simultaneously with the operation just explained, the hoisting piston G passes across the slot a¹ so that in consequence the compressed air contained within the hoisting tube is now enabled to escape through this slot in the atmosphere. Owing to its inertia, the charged hoisting piston rushes for a slight distance beyond the slot a¹ and forces in so doing the pawl O likewise outward. This latter, acting under the impulse of its spring o², returns immediately into its locking position so that now the piston G will come to seat itself on said pawl. In the meanwhile, the compressed air flowing through the pipe 4 above the distributing valve L into the casing K, has caused the return of the said valve into its lowermost position, and thereby cut off the supply of compressed air to the cylinder J and the hoisting tube A, and moreover cleared the path for the compressed air contained within the cylinder J so that it may now escape into the atmosphere through the pipes 2 and 8. Charging tube and hoisting tube being now no longer pressed together, an air gap comes to be formed at their faces of junction.

After the hoisting piston G has reached the place where the ammunition is to be taken off and the ammunition has been removed, the pawl O is released by a pressure on the handle o¹, whereupon the hoisting piston G drops by its own weight. The air present under the piston escapes through the gap now existing between the charging and the hoisting tube. As soon as the hoisting piston G has passed this gap, it compresses the air contained within the charging tube, and the air-cushion thus formed causes the hoisting piston to gently settle down on the bottom of the charging tube. Finally the body D is swung out, together with the charging tubes F at an angle of 180°. At the same time as the body D is being swung outward, the second tube F, which had meanwhile been charged, is positioned underneath the hoisting tube A, and the operation, as hereinabove set forth, begins afresh.

The form of execution disclosed in Fig. 3 differs from the construction just described solely by a modified form of the main control.

In this case a controlling shaft 10 carries a crank 11 connected to a spring-loaded piston 12¹ arranged within a cylinder 12. A pipe 21 runs from the cylinder 12 underneath the seat of a valve 13, which can be opened by aid of a hand lever 13¹. A pipe 20 connected to the compressed air receiver P terminates in the valve box above the seat of the valve 13. Another pipe 26 extending from the cylinder 12 terminates below the seat of the valve N. The space above the seat of said valve N communicates with the atmosphere by means of a pipe 27. On the controlling shaft 10 there are mounted three cam discs 14, 15, 16 adapted to act upon the stems of three valves 17, 18, 19. Two pipes 22 and 24 running from the receiver P terminate in valves 18 and 17, respectively, above the seats thereof. The space underneath the seat of the valve 18 communicates, on the one hand, by means of a pipe 23 with the cylinder J, and, on the other hand, by means of a pipe 28 with the space above the seat of the valve 19, while the space below this seat communicates with the atmosphere. From the valve 17 there runs a pipe 25 to the flange a² of the hoisting tube A, while a pipe 25¹ is connected to the flange f² of each charging tube F.

The manner of operation of this second form of execution is as follows:

On the valve 13 being opened, the compressed air flows through the pipes 20, 21 underneath the piston 12¹ and forces it upward counter to the action of the spring acting upon it, so that the shaft 10 is caused to rotate by the intervention of the crank 11. This again causes the valves 18 and 17 to be opened in succession by aid of the cam discs 15 and 14, while the valve 19 is closed. By first opening the valve 18, compressed air is allowed to flow out of the receiver P through the pipes 22, 23 to the underside of the ram H, so that the charging tube F is pressed against the hoisting tube A. Upon valves 17 being now opened, the compressed air flows through the pipes 24, 25, 25¹ underneath the hoisting piston G. As soon as this latter encounters the roller m¹, the valve N is opened by the bell crank lever M and the space underneath the piston 12¹ by these means brought in communication with the atmosphere through pipes 26, 27. The result of this arrangement is that the piston 12¹ is again moved downward by the action of its spring and the shaft 10 again returned into its initial position. Consequently the valves 17 and 18 are now closed while valve 19 is opened. Then the compressed air contained within the cylinder J is free to escape to the atmosphere through the pipes 23 and 24.

28 across valve 19, so that now the close connection between the charging tube and the hoisting tube will be again interrupted.

Claims:

- 5 1. An ammunition hoist of the class described comprising a hoisting tube, a charging tube adapted to be swung underneath the hoisting tube and to be shifted in the direction of the hoisting tube and fluid-pressure means for shifting the charging tube and closing the connection between said charging tube and hoisting tube. 60
- 10 2. An ammunition hoist of the class described comprising a hoisting tube, a charging tube adapted to be swung underneath the hoisting tube, a fluid-pressure operated ram disposed so as to engage the charging tube, means for supplying fluid-pressure to said ram whereby said charging tube will be 65 pressed toward said hoisting tube to close the connection therebetween. 70
- 15 3. An ammunition hoist of the class described comprising a hoisting tube, a charging tube adapted to be swung underneath the hoisting tube, fluid-pressure operated means for pressing said charging tube against said hoisting tube to close the connection therebetween, a fluid operated hoisting piston working in said charging and 75 hoisting tubes and means mounted on said hoisting tube in the path of said hoisting piston and connected to said fluid-pressure means whereby the pressure against said charging tube is automatically released 80 when said hoisting piston reaches the ammunition discharge end of said hoisting tube. 85
- 20 4. In an ammunition hoist a hoisting tube, a charging tube adapted to be swung underneath said hoisting tube, fluid-pressure operated means for pressing said charging tube against said hoisting tube to close the connection therebetween, a fluid-pressure operated hoisting piston movable through 90 said charging and hoisting tubes, means disposed in the path of said hoisting piston and adjacent the discharge end of said hoisting tube for releasing the closing pressure against said charging tube whereby as said 95 hoisting piston descends, its fluid-pressure operating medium may escape through the gap established between the hoisting tube and the charging tube, said operating medium being compressed within the charging tube by the hoisting piston thereby providing a cushion for the same. 100
- 25 5. In an ammunition hoist of the class described a hoisting tube, a charging tube adapted to be swung underneath the hoisting 105 tube, fluid-pressure means for pressing said charging tube against the hoisting tube to close the connection therebetween, a hoisting piston movable through said charging and hoisting tubes, means for conveying fluid-pressure to the underside of said hoisting piston to operate the same, said means extending through the connection between said hoisting tube and charging tube whereby said hoisting piston may be operated only when said connection is established between said charging and hoisting tubes. 110
- 30 6. An ammunition hoist comprising a hoisting tube, a displaceable charging tube adapted to be swung underneath the hoisting tube, a fluid-pressure operated ram disposed so as to press said charging tube against said hoisting tube, a hoisting piston working in said charging and hoisting tubes, means including a control device for successively supplying fluid-pressure to said ram and hoisting piston, means connected to said control device and operated by said hoisting piston as it reaches the discharge end of said hoisting tube whereby said control device will release the fluid-pressure acting upon said ram and said hoisting piston, substantially as and for the purpose set forth. 115
- 35 7. An ammunition hoist of the class described comprising a hoisting tube, a displaceable charging tube adapted to be swung underneath the hoisting tube, a fluid-pressure operated ram disposed so as to press said charging tube against said hoisting tube to establish a closed connection therebetween, a hoisting piston working through said charging and hoisting tubes, a fluid-pressure supply means including a control device connected so as to successively supply a fluid operating medium to said hoisting piston and ram, a valve connected to said control device and means mounted on said hoisting tube in the path of said hoisting piston and operated thereby for automatically operating said control device through said valve whereby pressure beneath said hoisting piston is cut off to permit said piston to return to its initial position and pressure beneath said ram is released. 120

The foregoing specification signed at Kiel, Germany, this 4th day of November, 1920.
